INVENTOR

Robert A. Komar.
By Paepkeich
ATTORNEY

UNITED STATES PATENT OFFICE

ROBERT A. KOMER, OF ST. LOUIS, MISSOURI

CONTAINER FOR CIGARETTES.

Application filed March 24, 1924. Serial No. 701,456.

This invention relates to a certain new and useful improvement in cigarette-containers and has for its chief object the provision, as a new article of manufacture, of a container 5 integrally combining a chamber or receptacle for a package or quantity of cigarettes and safety matches with lighting means for the contained cigarettes, the container as a whole being of simple and inexpensive construction, compact in form, and efficient and convenient in use.

With the above and other objects in view, my present invention resides in the novel features of form, construction, arrangement, 15 and combination of parts hereinafter described and afterwards pointed out in the claims.

In the accompanying drawing,

Figure 1 is a perspective view of a container embodying my invention;

Figure 2 is a plan view of the container;

Figure 3 is an open plan view of the scored or divided blank employed in the formation of the container; and

Figure 4 is a view of the panel-providing blank as folded in the formation of the container.

Referring now more in detail and by reference characters to the drawing, which illustrates a preferred embodiment of my invention, A indicates the container blank, which is preferably of any suitable relatively flexible or bendable material, such as, for instance, paper, light-weight card-board, or the like. The blank A, which is approximately of rectangular-oblong form, is of suitable dimensions, length and breadth, as may be desired in the height, width, and capacity of the finished or complete container, and is transversely scored or otherwise marked for convenient folding at spaced intervals throughout its length, as at 1, 2, 3, 4, 5, 6, 7, 8, 9, and 10, and is thus integrally divided into a plurality of adjoining panels adapted to form the top, rear, and opposite side walls of the body-portion or match-compartment of the container.

As so constructed and scored or otherwise marked, the blank A is folded upon the lines 1, 2, 3, 4, 5, 6, 7, 8, 9, and 10 into container-form, the blank end-panel 11 being brought over into flatwise registration with and pref-

erably adhesively fixed to the intermediate panel 12, which latter panel is disposed between the folding lines 8 and 9. The intermediate blank-panels 13 and 14, which are, respectively, disposed between the folding lines 3 and 4 and 4 and 5, are then folded not only approximately flatwise together, but also, as best seen in Figure 4, to overlie a side margin of the intermediate blank-panel 15, which latter panel is disposed between the folding or bending lines 1 and 2.

A strip including a plurality of ordinary or common so-called breakable paper safety-matches, or cigarette-lighting members B, as I term them, is then disposed flatwise upon the blank-panel 15, the strip proper being interposed under the overlying flap formed by the flatwise registering intermediate blank-panels 13 and 14, the thickness of such match strip being accommodated by the folded and also substantially registering intermediate corner blank-panels 16 and 17, which are, respectively, disposed between the folding lines 2 and 3 and 5 and 6. By means then of suitable fastening means, such as, for instance, and preferably the staples C passed through the overlapping or flap blank-panels 13 and 14, the match-strip B, and the underlying blank-panel 15, not only is the blank A securely held in finished container form, its one end-panel 11 being, as stated, adhesively fixed flatwise to and upon the intermediate blank-panel 12, but the match-strip B is firmly and permanently attached to and forms substantially an integral part of the container.

With the blank A so folded and secured, its said flatwise disposed and fixed together panels 11 and 12 form one side wall of the container, its intermediate-panel 18, which resides between the folding-lines 6 and 7, forms the opposite side wall of the container, and its intermediate-panels 15 and 19, which latter panel resides between the folding lines 7 and 8, form, respectively, the top and bottom walls of the container, the opposite blank end-panel 20 folding smoothly and substantially flatwise over and upon and providing a cover for the matches B, as clearly seen in Figures 1 and 2. As will be evident, and as illustrated in Figure 2, the free edge of the flap or match-cover 20 may be conveniently disposed and releasably secured

under the match-overlapping flap formed by the panels 13 and 14, the thickness of the strip and matches B being accommodated at the attached edge of flap 20 by the intermediate corner blank-panel 21 which resides between the folding-lines 9 and 10.

At one side edge, the blank A is further divided, as at 22 and 23, to also comprise panel-extensions which are adapted to provide or form end-flaps 24 and 25, the latter flap 25 being also scored or otherwise marked for folding, as at 26, 27, 28, and 29. As so scored or marked, the flap 24 is first folded downwardly and the flap 25 then, at the lines 26, 27, 28, and 29, folded, as best seen in Figure 4, inwardly and upwardly upon and secured, preferably adhesively, to the flap 24 to form the end-wall of the container.

The finished container is thus approximately rectangular in form and provides an open-end convenient and handy receptacle for a quantity of cigarettes shown in the present instance in package-form, as at D, sealed in the container as an original package by means of a stamp or the like E.

My new container may be easily constructed either manually or by machine and provides ready at hand matches for the lighting of the several contained cigarettes as they are removed from the package. It will be evident that, if desired, the container may be constructed of sufficiently strong and durable material to enable its repeated employment as a carrier of cigarettes and the like; preferably, however, the container is inexpensively constructed for discarding on removal of the original package of cigarettes and, to that end, is equipped with matches B substantially corresponding in number with the contained cigarettes, for the convenient lighting or ignition of which matches the container is also preferably provided with a suitable emery or scratching surface, as at 30, upon the exposed blank-portion or flap 14.

I am aware that changes in the form, construction, arrangement, and combination of the several parts of the container may be made and substituted for those herein shown and described without departing from the nature and principle of my invention.

Having thus described my invention, what I claim and desire to secure by Letters Patent is:

1. As an article of manufacture, a cigarette-container comprising a cigarette-holding body-portion constructed of a section of flexible material divided into a plurality of adjoining panels and folded upon itself, whereby one end-panel and an intermediate panel jointly form one side-wall of the container body-portion, other intermediate panels form, respectively, the opposite side and the top and bottom walls of the container body-portion, still other intermediate

panels jointly form a flap overlying a marginal portion of the top wall, and the opposite end panel forms a second flap opposed in direction to the first flap and adapted to swingably overlie a portion of the top wall.

2. As an article of manufacture, a cigarette-container comprising a cigarette-holding body-portion constructed of a section of flexible material divided into a plurality of adjoining panels and panel-extensions and folded upon itself, whereby one end-panel and an intermediate panel jointly form one side-wall of the container body-portion, other intermediate panels form, respectively, the opposite side and the top and bottom walls of the container body-portion, still other intermediate panels jointly form a flap overlying a marginal portion of the top wall, the opposite end panel forms a second flap opposed in direction to the first flap and adapted to swingably overlie a portion of the top wall, and said panel-extensions jointly form an end-wall of the container body-portion.

3. As an article of manufacture, a cigarette-container comprising a cigarette-holding body-portion constructed of a single section of flexible material integrally divided into a plurality of adjoining panels and panel-extensions and folded upon itself, whereby one end-panel and an intermediate panel are disposed in flatwise relation for permanent connection and jointly form one side-wall of the container body-portion, other intermediate panels form, respectively, the opposite side and the top and bottom walls of the container body-portion, still other intermediate panels are disposed in flatwise relation for permanent connection and jointly form a flap overlying a marginal portion of the top-wall, the opposite end panel forms a second flap opposed in direction to the first flap and adapted to swingably overlie a portion of the top-wall, and said panel-extensions are disposed in opposed relation and jointly form an end-wall of the container body-portion, said one end and intermediate panel and said other intermediate panels being, respectively, fixed together in side-wall and flap-forming relation.

4. As an article of manufacture, a cigarette-container comprising a cigarette-holding body-portion constructed of a single section of flexible material integrally divided into a plurality of adjoining panels and panel-extensions and folded upon itself, whereby certain of the panels form the side and top and bottom walls of the container body-portion, certain of the intermediate panels are secured together in flatwise relation and jointly form a flap overlying a marginal portion of the top-wall, an end panel forms a second flap opposed in direction to the

first flap and adapted to swingably overlie a portion of the top-wall, and said panel extensions are disposed in opposed relation and jointly form an end-wall of the container body-portion, in combination with a strip disposed and fixed intermediate said first flap and said top wall, and a lighting-

member projecting from said strip to flatwise extend for removal lengthwise upon said top-wall, said second flap providing a 10 swingable cover for the lighting member.

In testimony whereof, I have signed my name to this specification.

ROBERT A. KOMER.
